UNITED STATES PATENT OFFICE.

JOHN D. GAINES, OF CARNEYS POINT, NEW JERSEY.

LUNCH-BOX FASTENER.

1,285,112.

Specification of Letters Patent. Patented Nov. 19, 1918.

Application filed November 23, 1917. Serial No. 203,590.

To all whom it may concern:

Be it known that I, JOHN D. GAINES, a citizen of the United States, residing at Carnegy Point, in the county of Salem and State of New Jersey, have invented certain new and useful Improvements in Lunch-Box Fasteners, of which the following is a specification:

This invention relates to an improved lunch box fastener, and the principal object of the invention is to provide a fastener of the hasp and wedge type so constructed that the wedging bridge may be slidably mounted upon the hasp and brought into engagement with a tongue secured upon the lunch box to securely but releasably hold the cover in a closed position.

Another object of the invention is to so construct this fastener that when in an operative position, there will be no danger of it accidentally slipping out of place and releasing the cover.

Another object of the invention is to so construct this fastener that it will be simple in construction and comprises a comparatively few number of parts, easy to operate and not liable to quickly get out of order.

This invention is illustrated in the accompanying drawings, wherein:—

30 Figure 1 is a view showing the improved lunch box in front elevation.

Fig. 2 is a vertical transverse sectional view through the lunch box taken along the line 2—2 of Fig. 1,

35 Fig. 3 is a fragmentary sectional view taken along the line 3—3 of Fig. 1.

This lunch box is provided with a body or receptacle 10 having a cover 11 hingedly connected with the body as shown at 12 and 40 provided with a carrying handle 13. The socket member carried by the receptacle is provided with a base plate 14 and tongue 15 extending from the base plate in spaced relation to the body. If desired this socket member may be formed of resilient material to provide a good binding engagement between the tongues and the bridge or slide 45 16 slidably mounted upon the arm of the hasp 17. This hasp has its arms bent to provide outstanding feet 18 mounted in bearings 19 thus pivotally mounting the hasp and permitting it to be swung upwardly out 50 of engagement with the socket member

when the slide or wedging bridge 16 has been moved upwardly. When the lid or 55 cover 11 is closed and it is desired to secure the cover, the hasp will be swung downwardly to the position shown in the drawing and the bridge 16 then slid downwardly between the tongues 15 and the front wall of 60 the body. The bridge will wedge in place and the hasp will thus be held beneath the tongues 15 as shown in Fig. 2 and the cover will be prevented from opening. By moving the bridge upwardly above the 65 tongues, the hasp will be released and can be swung upwardly thus permitting the cover to be raised.

It will thus be seen that there has been provided a fastener of a simple construction 70 and at the same time a fastener which will securely hold the cover in a closed position. It will be further noted that when in the operative position, there will be no danger of the bridge slipping as this bridge will be 75 tightly wedged in place and will be held securely in place by the frictional binding between the bridge and the tongues. It will be further noted that it does not require any special construction of lunch box for 80 use in connection with this fastener thus permitting the fastener to be applied to lunch boxes of a conventional construction.

What is claimed is:—

1. A receptacle having a body, a cover 85 for the body, a socket member carried by the body and provided with a base plate and a tongue extending from the base plate in spaced relation to the body, a hasp pivotally connected with the cover and when in an op- 90 erative position swung down beneath the tongue of the socket member, and a wedging bridge slidable upon the arms of the hasp and fitting between the tongue and body and engaging the inner face of the tongue. 95

2. A receptacle having a body and a cover for the body, a socket member carried by the body, a hasp member carried by the cover and extending about the socket member when in an operative position, and a wedg- 100 ing member carried by the hasp and frictionally engaging the socket member to releasably hold the hasp in an operative position.

3. A receptacle comprising a body having 105 a cover mounted thereon, the said body car-

22
rying a tongue extending in spaced relation to the body, a hasp pivotally connected to the cover, and means slidably mounted upon the hasp and adapted to be wedged into the space between the tongue and the said body when the said hasp is swung to operative position.

Copies of this patent may be obtained for five cents each, by addressing the "Commissioner of Patents, Washington, D. C."

In testimony whereof I affix my signature in presence of two witnesses.

JOHN D. GAINES.
